[57] CLAIM

The ornamental design for a set of terminals for battery booster cables, as shown and described.

DESCRIPTION

FIG. 1 is a front, top and side perspective view of a set of terminals for battery booster cables showing my new design with the insulator sleeve separated from the negative terminal;

FIG. 2 is a front elevational view a set of terminals for battery booster cables showing my new design with both terminal insulator sleeves in place;

FIG. 3 is a side elevational view thereof, the side opposite being a mirror image of the side shown in FIG. 3;

FIG. 4 is a top plan view thereof; and,

FIG. 5 is a bottom plan view thereof.

FIG. 2

FIG. 4

FIG. 5

FIG. 3
